UNITED STATES PATENT OFFICE.

FRANK C. CALDWELL, OF CHICAGO, ILLINOIS.

PULLEY.

SPECIFICATION forming part of Letters Patent No. 295,732, dated March 25, 1884.

Application filed September 4, 1883. (No model.)

To all whom it may concern:

Be it known that I, FRANK C. CALDWELL, of Chicago, in the county of Cook and State of Illinois, have invented a certain new and useful Improvement in Pulleys, of which the following is a full, clear, and exact description, reference being had to the accompanying drawings, forming part of this specification, and in which—

10 Figure 1 is a face view, part broken away; and Fig. 2 is a vertical section. Fig. 3 represents another manner of securing the rim to the disk or body.

15 My invention relates to a belt-pulley; and it consists in making both the rim and body or disk of a plurality or multiple of veneers, as more fully described hereinafter.

20 Referring to the drawings, A represents the rim of the pulley, B the body or disk, C the hub, and D D plates for securing the disk or body to the hub. The rim is made of a plurality of veneers glued or otherwise secured together. Any suitable number of these layers may be used, and it would be desirable to 25 have the grain of the wood of the different layers run as much as possible in opposite directions. The disk or body is also made of a multiple or plurality of veneers, of any desired 30 number of layers, glued or otherwise secured together. The rim is preferably secured to the disk by turning the periphery of the latter outward in one or both directions, preferably in both, as shown in Fig. 2, forming a

flange, B', to which the rim is connected by rivets or otherwise; or, instead of thus turning the periphery of the disk out, angle-pieces E, (see Fig. 3,) of any desired length, may be employed for connecting the rim to the disk. The disk or body is secured to the hub by being clamped between two plates, D D, which are 40 connected by bolts or rivets passing through the disk, and one of which is formed upon or secured to the hub, as shown.

A pulley thus constructed is light, strong, and durable, and can be very cheaply produced.

I claim as my invention—

1. As a new article of manufacture, a pulley the rim and disk or body of which consist of a plurality of veneers, substantially as set forth.

2. A pulley the rim and disk of which consist of a plurality of veneers, the periphery of the disk being turned outward, forming a flange, to which the rim is secured, substantially as set forth.

3. In a pulley, the combination of rim A, made of a plurality of veneers, disk or body B, made of a plurality of veneers, hub C, and plates D, all made, constructed, and arranged substantially as specified.

FRANK C. CALDWELL.
